UNDERWATER SALVAGE DEVICE

Eugene J. Romano, Seattle, Wash.; Lula Romano
administratrix of said Eugene J. Romano,
deceased

Application March 27, 1933, Serial No. 663,029

9 Claims. (Cl. 61—69)

My present invention relates to the art of underwater salvaging and more particularly to an underwater salvage device.

The great wealth represented in sunken boats and the like in the ocean, at greater depths than the ordinary diver can descend, has prompted the development of many devices to aid in underwater salvage. My device is of this general class. It is characterized however by being so arranged that an operator can descend hundreds of feet below the surface of the water and by means of control arrangements manipulate two or more arms in a manner which makes it possible to execute any maneuver that could normally be done by the two arms of an individual. The method of supporting and maneuvering my salvage device has been gone into in some detail in my co-pending application entitled "Maneuvering means for underwater salvage equipment" Serial Number 663,030 filed March 27, 1933 has all the characteristics of the various diving bells which have been designed and constructed to permit an observer descending to great depths to assist in directing salvage operations, and in addition is provided with the mechanical arms which because of their unusual construction have proven to be of great value.

The principal object of my present invention is therefore to provide means in addition to a diving arrangement whereby salvage operations can actually be conducted by the observer.

A further object is the provision of means whereby the mechanical arms of my diving device can be operated in the same manner as the arms of an individual.

A further object is the provision of means whereby the power applied to the arms of my device can be so increased that the device can be used to handle the heavy cables and chains, lift heavy objects and the like which marine salvage requires.

Other and more specific objects will be apparent from the following description taken in connection with the accompanying drawings, wherein,

Figure 1 is a top plan view of my device showing both arms in their extended position.

Figure 2 is a side elevation showing both arms in a partially folded position.

Figure 3 is a vertical elevation in section showing elements of my control mechanism.

Figure 4 is a view similar in part to Figure 3 but taken at right angles to that view.

Figure 5 is an enlarged fragmentary view show-

ing in sectional elevation the control means for one of my mechanical arms.

Figures 6 and 7 are enlarged fragmentary views showing further control means of the mechanical arms.

Figure 8 is a fragmentary view partly in section showing the outward end of one of my mechanical arms.

Figure 9 is a plan view partially in section of the inner of the same mechanical arm.

Figure 10 is a side elevation of a portion of Figure 8.

Figure 11 is an end view of the mechanical arm showing one form of attachment for use thereon.

Figure 12 shows, in modified form, the inner end of one of the mechanical arms.

Referring to the drawings, throughout which like reference characters indicate like parts, 14 designates the main body of my diving chamber. This I normally prefer to form as a casting because of the irregular shape which conditions require and it is rather essential that the material from which this casting is made be somewhat malleable. In case the bell should accidentally be dropped short distances under water or meet with a very sharp blow from any source it is desirable that the shell will bend rather than crack because even every small crack at the lower levels, where the water pressure is tremendous, would be disastrous for the operator. I have found cast steel, providing it is of close grain, a very desirable metal. Some of the bronzes or brasses might be very satisfactory also. It is desirable to provide the bell of sufficient size that one or more operators can conveniently move around in the same as there are a large number of controls and it is rather essential that the operator have a certain degree of comfort in that he may out of necessity be required to stay under water for several hours at a stretch. Air must of necessity be supplied to the operator. This can be handled in any of the well known ways and as it forms no particular part of my present invention I do not believe it will be necessary to go into detail in this matter. No matter what form of supply is provided it is very desirable to, in addition, supply the bell with an available supply of oxygen and some device for the absorption of carbon dioxide as conditioner 15. This equipment is well known in submarine work however.

The diving chamber is normally supported by a rather heavy cable 16 attached to the bell usually by means of the ring 17 which in turn is secured to the bell by a plurality of welded on straps 18. This cable should be of sufficient strength to not

only support the buoy at all times but to support the buoy if the arms are engaged with some device it is desired to salvage and further should have additional strength in that if the maneuvering cable 20 should be come entangled or if the air supply or telephone and electric cable become entangled that there will be sufficient strength in the hoisting cable to break the other lines and make it possible to hoist the chamber to the 10 surface.

The diving chamber can further be provided with a plurality of heavy glass port lights as 21, disposed in various positions around the bell at a height and in positions where the operator 15 or operators will have clear vision of the work they are undertaking. As a means of exit and entry into the bell I provide the manhole cover arrangement at 22. This is preferably of the type that seats from the outside on a gasket so 20 that the pressure over this relatively large surface will tend only to make the sealing of this opening more secure. Any desired form of fastening may be used. I have indicated the usual cross bar and bolt arrangement quite common 25 in manholes on boilers and the like. The various items enumerated are more or less common in diving bell arrangements. It is believed that possibly the principal novelty of this present application resides in the most unusual and efficient 30 construction of the maneuvering arms designated generally by 23 and 24.

A general idea of this construction will be most easily understood from Figures 1 and 2 as supplemented by the details used of Figures 8, 9, 10 35 and 11 and the various large sectional views. The arms are pivotally supported as on shafts 26. I normally prefer that these shafts be horizontally disposed with reference to the bell although there is nothing to prevent placing them 40 in a vertical or angled position. Merely a matter of simplification of the control arrangement favors the horizontal position. The arm construction will probably be best and most clearly disclosed in Figures 8, 9 and 10. Encircling shaft 45 26 which is additionally supported by the out-board bearing 28 is a hollow shaft as 29. This hollow shaft 29 should be rather carefully machined to provide a journal on shaft 26 to the end that it will cooperate with shaft 26 in supporting the arm about the axis of shaft 26. The two side members 30 and 31 support the arm and 50 guide it as it revolves about the axis of shaft 26. The actual movement of the arm however is provided by fixedly securing side frame 38 to the hollow shaft 29. This then places the movement of the arm under control of shaft 29. Shaft 29 has fixedly secured to it an operating lever 33 which in turn is under control of the hydraulic cylinder 55 35. This cylinder may be provided with hydraulic pressure from any source. However, it has been found most convenient to use a manual pump as 36 which is energized by the hand lever 37. With such an arrangement as this, which is really a hydraulic jack, it is possible to place 60 tremendous loads upon the arms in the outwardly or extended positions yet have it under easy and positive control at all times. I have indicated set screws as providing the attachment between the side frame member and the operating lever and 65 the hollow shaft 29. Actually this attachment should not rest upon set screws, they should be brazed or welded in place preferably. All the way thru the construction of this machine it must be borne in mind that it is imperative that there 70 75 be no leakage at any point, which the extremely

high pressures encountered would soon find. To this end the hollow shaft 29 should be provided with a packing gland as I have indicated at 38.

The movement just explained is comparable in the human arm to the shoulder movement. 5 Then it is desirable to have a movement similar to the elbow movement. This is provided at 40 where a yoke fitting 42 engages an elbow pivot pin 43 upon which the outward portion of the arm is free to revolve, under control only of the bevel 10 gear arrangement 44 and 45. Gear 45 which I normally prefer to have larger than the driving pinion 44, is fixedly secured to at least one of the side members of the outer arm portion as 46.

The outer end member is controlled about pin 15 43 by means of the pinion gear 44 which is fixedly secured to shaft 48 and which in turn has fixedly secured to it the bevel gear 50. This gear is in mesh with and is operated by gear 51 which in turn is fixedly secured to shaft 26. Now it often 20 devolves upon this mechanism to hold the entire weight, not only of the outer arm member but also any weight that it may have picked up. As a result it is necessary to provide operating means which will give the operator every mechanical 25 advantage possible without unduly complicating the mechanism. This is attained by means of the hand lever 52 which is pivotally supported on shaft 26 and has the two way dog arrangement 30 53. This may be set to move the shaft either 35 direction and this operation is completed by means of locking spring 54 which is provided with two positions for engagement of the outstanding lug of the dog member 53. One position is indicated at 55, the other as 57. Any form of 40 double acting dog arrangement would be useable in this instance, altho the toggle arrangement shown has proven very satisfactory. Now it must be remembered that the operator is called upon normally to handle two arms quite often at the 45 same time. As a result it is necessary to provide means so that one hand can handle the complete operation of a single arm. To this end it was found desirable to provide a foot controllable latch as 60 which is pivotably supported to a fixed 50 pivot and is operated thru the control rod 61 by the foot lever 62. A tension spring as 63 is found desirable to keep latch 60 at all times in mesh with the ratchet gear 64 which is fixedly secured to shaft 26, it being apparent it is believed from 55 Figure 6, that the dog or latch will always be engaged except when pressure is applied to foot lever 62. In this way the operator has complete control of this movement of the arms under action of one hand and one foot. I have described but one mechanism for each arm. It will be clear it is believed that this equipment 60 must be duplicated for each arm.

Now, it must be understood that the exact details of construction in a design of this character must necessarily follow the conditions under which the device is to be used. I have shown in Figures 1 and 2 that the arms, while substantially the same, have the pivot pin 43 disposed in opposite planes. This is very desirable in that it gives a more complete control and it permits almost any movement required of the arm. There are times however, when it may be desirable to tie knots and the like with this equipment and under such conditions it is found that the limiting of the movement of the arm about its longitudinal axis is somewhat objectionable. To overcome this feature I have provided a slight modification of my device.

The modification is shown in Figure 1 and 75

Figure 12, Figure 1 showing the general view and Figure 12 showing the details of construction. This arrangement follows very closely that described and shown in Figure 9 with the 5 added feature however, that a second hollow shaft as 67 encircles shaft 26 and this is fixedly secured to a beveled gear 68 which meshes and drives in turn bevel gear 69. This revolves shaft 70 and in turn pinion 71 which is secured thereto. Suitable bearings are provided for 10 shaft 70 which are fixedly secured to the inner arm portion. Gear 71 is adapted to engage in driving relationship the spur gear 72 which is fixedly secured to the yoke member 73 which is 15 similar in many respects to the yoke member 42. With this arrangement it will be apparent that the outer end of the arm can be revolved about its longitudinal axis as may be desired. It would necessarily be desirable to have a lock- 20 able operating means similar to that described for shaft 26.

In this modified form hollow shaft 67 must carry the load of and serve all functions of shaft 26 of Figure 9 so that the solid shaft 26 can 25 serve this modified purpose.

It has been found that for such mechanical arms to be of real value they must be capable of grasping very securely any weight that the arrangement can lift and further that that engagement or release should be capable of rather quick operation. To this end I have provided the two jaw members 75 and 76 which should have notches or teeth which will best adapt them to the type of work in mind. These members are pivotably supported at 77 and 78 on pivots 10 which are in turn secured to the arm housing proper. Each jaw member has cut on it a segment of the gear which meshes together so that any movement of one of the jaw members will be transmitted in equal amount to the other. Each jaw member has a rearwardly extending arm as 79 and 80 which terminates with a bifurcation adapted to receive the ground rollers as 82 and 83 respectively. These rollers are suitably journaled on pins secured in the arm 19 and 80. Adapted to engage the grooved rollers is a V-shaped cam member 84 which is mounted for reciprocating movement along the axis of the arm. Secured to the V-shaped cam member by suitable adjustable means is the piston rod 85 which at its opposite end is connected to the piston member 86. To prevent unnecessary machine work I provide a cylinder proper as 87 in which the piston reciprocates. A large coil spring as 88 is provided to normally urge the piston to the inner limit of the cylinder and a stop is provided as 90 to limit the inward movement. As shown in Figure 8 it may appear that the outward end of the cylinder housing is entirely closed which is not true as is more clearly illustrated in Figure 10 in which the supporting strap 91 is shown to be of a width considerably less than the width of the cylindrical arm member 92. This provides for the easy ingress of water at this point so that at all times, up against the inner end of the piston, will be the normal hydro-static pressure corresponding to the depth the bell is lowered to.

Power to operate piston 86 and indirectly the 70 jaw members 75 and 76 is developed thru a hydro-pneumatic arrangement in which a liquid such as water is supplied thru the flexible tube 93. This tube is connected to the bottom of the power cylinder 94 which is normally filled with 75 water preferably containing a lubricant to such

an extent that when the piston is in its outward extreme travel there will still be some liquid left in cylinder 94. Pressure is applied to the liquid from a high pressure gas tank 95. This pressure is controllable thru suitable valves as indicated in Figure 4 and the pressure is recorded on a pressure gauge 96. When it is desirable to release the jaws the valve in the line to flask 95 is closed and valve 97 open. This provides an escape for the gas now under considerable pressure to the outside. In this connection it is desirable to point out that it is necessary that the normal pressure of the water be exerted against the inner or rod end of piston 86 so that the gas can be expelled out thru valves 97 against the water pressure by the action of spring 88, it being unnecessary for spring 88 to overcome any hydraulic pressure.

In Figure 11, I have shown in a fragmentary view additional jaws which may be secured to 20 jaw members 75 and 76. These consist of normally metal members which are bent at right angles to the normal plane of jaws 75 and 76 as indicated in Figure 11 so as to provide the jaws at 98 and 99 which are very useful performing some functions not possible with the other jaws.

Method of operation

The diving chamber is normally lowered by 30 cable 16 and after being lowered is guided to the desired position by means of the plurality of maneuvering lines 20. These maneuvering lines are attached to the floating ring 101 which in turn can be revolved by means of hand lever 102. This lever is constructed along the order of lever 52 in that it is a ratchet arrangement that is operable in either direction. By operating this lever it is possible for the workman to revolve the bell with respect to the maneuvering lines and thus place the mechanical arms in 40 the most advantageous position for the salvage operation. The operator then maneuvers the mechanical arms by the various controls cited until he is able to engage those items necessary in the completion of his salvage work. In constructing such a mechanism as this it is necessary for the builder to bear in mind that extreme depths are to be encountered which means very high hydraulic pressure and it is essential that the various arms be constructed so that 50 the water can circulate around and thru them to the end that no binding of the various parts will occur thru any pressure being able to press any of the parts tightly together.

The foregoing description and the accompanying drawings are believed to clearly disclose a preferred embodiment of my invention but it will be understood that this disclosure is merely 60 illustrative and that such changes in the invention may be made as are fairly within the scope and spirit of the following claims.

Having thus fully described my invention, what I claim as new and desire to secure by Letters Patent is:—

1. The combination with a submarine vessel, 65 of a non-rotatable main, tubular arm, a power shaft journaled in the vessel and a tubular control shaft surrounding the power shaft and journaled in the vessel, said arm having a rigid connection with the tubular shaft exterior of the vessel and a pivotal bearing on the power shaft whereby the arm may swing in a plane parallel with the vertical axis of the vessel, means for turning the tubular shaft and means for turning 70 75

the power shaft, a forearm pivoted on the main arm and a segmental rack rigid with the forearm, a counter shaft journaled in the main shaft, transmission gears between the power shaft and the countershaft, and a pinion on the counter-shaft engaging said segmental rack.

2. The combination with a submarine vessel, a non-rotatable main tubular arm adapted to swing in a plane parallel with the vertical axis of the vessel, a power shaft arranged transversely of the arm and journaled in the vessel and a tubular control shaft surrounding the power shaft and journaled in the vessel, said arm having a rigid connection with the tubular shaft and a bearing on the power shaft, separate means for turning said shafts, a tubular forearm having a clamping jaw at its free end, a pivotal connection between the forearm and the main arm whereby the former may be swung in a vertical plane, a countershaft journaled in the main arm and a gear couple between said shaft and the power shaft, a segmental rack on the forearm and a pinion on the countershaft engaging said rack, and means for operating said clamping jaw.

3. The combination with a non-rotatable arm having a head at its free end, a pair of jaws pivoted in said head, and intermeshing gears on said jaws, of lever plates on said jaws and a spring tending to close the free ends of said plates, anti-friction rollers journaled in the free ends of the plates, a wedge shaped spreader engaging said rollers, and means for reciprocating the spreader.

4. The combination with an arm having a head at its free end, a pair of jaws pivoted in said head, intermeshing rack gears on said jaws, and a spring tending to open the jaws, a pair of plates rigid with the jaws and anti-friction rollers journaled at the free ends of the plates, a reciprocable, wedge-shaped cam mounted on the arm and engaging said rollers, means for retracting said cam, and means for projecting said cam to close the jaws.

5. The combination with a tubular arm having a head at its free end, a pair of spring-opened jaws pivoted in said head and co-acting pivotal devices on said jaws, of a pair of plates rigid with the jaws and anti-friction rollers journaled therein, a reciprocable wedge-shaped cam engaging said rollers and mounted in the arm, a motive fluid cylinder mounted in the tubular arm and means for supplying motive fluid thereto, a piston in the cylinder and a piston rod connecting said piston and cam, and a retracting spring in the cylinder for said cam.

6. The combination with a tubular arm having a head at its free end, a pair of spring-opened jaws pivoted in said head, intermeshing rack gears on said jaws, spreader plates mounted on said jaws, and anti-friction rollers journaled in the free ends of said plates, of a reciprocable wedge shaped cam mounted in the arm and engaging said rollers, a motive fluid cylinder mounted in the tubular arm and a motive fluid supply thereto, a piston in the cylinder adapted to receive fluid pressure at one side thereof and a retracting spring at the other side of the piston, and a piston rod connecting the piston and the cam.

7. In submarine apparatus, the combination with a vessel-support and a relatively revolvable vessel, of a non-rotatable main arm having an exterior pivot on the vessel and adapted to swing in a plane parallel with the vertical axis of the vessel, means within the vessel for swinging said arm, a forearm revolvably mounted on the main arm to turn on its longitudinal axis, a pivotal connection between said arms to permit the forearm to swing in a vertical plane, clamping jaws at the free end of the forearm, and means for operating said jaws.

8. The combination in a submarine vessel with an outer tubular control shaft and means for turning said shaft and a main arm fixed to said shaft to turn in a plane parallel with the vertical axis of the vessel, of a head journaled to turn on its axis in said main arm and a forearm pivoted in said head, an inner tubular shaft and means actuated thereby to swing said forearm on its pivot, a solid shaft within the inner shaft, and means actuated by the last shaft to revolve the head and forearm with relation to the main arm.

9. The combination in a submarine vessel with an outer tubular control shaft and means for turning said shaft, a frame fixed to said shaft, and a tubular main arm fixed to the frame to swing in a plane parallel with the vertical axis of the vessel, a head mounted on the free end of the main arm to rotate on the longitudinal axis of the main arm, a forearm pivoted in said head, an inner tubular shaft, a countershaft journaled in the main arm and a gear couple between said shaft and the inner tubular shaft, a gear mounted between the head and pivoted forearm and a pinion on the countershaft engaging said gear, a shaft within the inner tubular shaft, a gear ring mounted on the head, a gear shaft supported on the main arm and a gear-couple between said shaft within the inner tubular shaft, and a pinion on the gear shaft engaging said gear ring.

EUGENE J. ROMANO. 55
